1

The present invention relates to pulse modulation, more particularly to a novel method and system for converting time modulated signal pulses into corresponding amplitude modulated pulses for demodulating or reproducing a signal wave in a receiving station.

When signals or messages are transmitted by means of time-modulated pulses there is a difference, according to whether the width or the position of the pulses is modulated. With width-modulated pulses, the width, that is to say the duration of successive pulses, corresponds to the instantaneous values of a modulating signal. With position-modulated pulses, the degree of modulation is characterized by the distance in time of one or both edges of the pulses from equidistant instants. Time-modulated pulses are demodulated by first converting them into amplitude-modulated pulses. Thereupon, the actual demodulation to the original modulating signal occurs. When converting the width-modulated or position-modulated pulses into amplitude-modulated pulses, it is desirable that the conversion should be as free from distortion as possible.

The present invention is concerned with an improved method and arrangement for achieving this conversion. According to the novel method, signal voltage values proportional to the time values characterizing the modulation of the time-modulated pulses are produced, at least part of said signal voltage values being stored, in such a manner as to result in pulses which occur at equal intervals and have an amplitude proportional to said voltage values.

Further objects and novel aspects of the invention will become more apparent from the following detailed description taken in reference to the accompanying drawings forming part of this specification, and wherein:

Figures 1, 2, 3a to 3d and 5a to 5d are theoretical diagrams explanatory of the function and operation of the invention; and

Figures 4 and 5 are wiring diagrams of suitable circuit arrangements for carrying out the invention.

Referring to Figure 1, J₁, J₂, J₃ etc. are time-modulated pulses shown for different degrees of modulation. The instants at which the pulses commence are characterized by the position of the left-hand pulse edges and follow each other at equal intervals of time T. The durations X₁, X₂, X₃ etc. of the pulses are the momentary time values which characterize the degree of modulation or instantaneous modulating signal values and serve to produce the time-proportional volt-

age values Y₁, Y₂, Y₃. These voltage values attain their values Y₁, Y₂, Y₃ at the end of each pulse, such as by charging a condenser with constant current during a time corresponding to the pulse durations X₁, X₂, X₃.

There are obtained in this manner amplitude modulated pulses Z₁, Z₂, Z₃ corresponding to the voltages Y₁, Y₂, Y₃. If these amplitude modulated pulses occurred immediately at the end of the pulses (right-hand pulse edge), as would be the simplest arrangement, they would not be spaced by equal intervals. This would result in nonlinear distortion at the output of the demodulator. According to the invention this distortion is avoided by making the amplitude-modulated pulses follow each other at equal intervals T'=T. This is achieved by storing the voltage values Y₁, Y₂, Y₃ and only allowing them to become effective at equidistant points in the form of the amplitude-modulated pulses Z₁, Z₂, Z₃. S₁, S₂, S₃ indicate the corresponding storage times. Thus, the amplitude-modulated pulse occurs only towards the end of an interval T. It is also possible to allow the pulse Z₁ to occur at the instant P₁ when the next pulse X₂ begins, since the pulses start at equal intervals. In all events, the amplitude-modulated pulses Z succeed each other at equal intervals T', that is at equidistant time positions, so that the demodulation will be linear and accurately follows the shape or curve of the original modulating voltage.

Another use of the method according to the invention relates to the demodulation of width-modulated pulses of the type shown in Figure 2. Here, the pulses are modulated in such a manner that the distance in time of both edges of the pulses from equidistant points P_{a1}, P_{b1}, P_{a2}, P_{b2}, P_{a3}, P_{b3} etc. serves as the time value characteristic of the instantaneous modulating signal values. Thus, the equidistant instants of time occur at double the pulse frequency, so that every second point P_{a1}, P_{a2} falls within a pulse, and the intervening points P_{b1}, P_{b2} fall within the gaps between the pulses. The time value a₁ measured from the left-hand pulse edge to the point P_{a1} corresponds to a proportional voltage value Y_{a1}. This voltage controls the pulse Z_{a1} in a linear relation. The time value b₁ corresponds to a voltage value Y_{b1}. At the instant when the pulse stops, the voltage Y_{b1} has also reached its end value. The pulse proportional to this voltage should not, however, occur at this instant, but somewhat later at the instant P_{b1}. According to the invention, the voltage Y_{b1} is therefore stored during the time S₁. The same process repeats itself with all the sub-

sequent pulses. The modulation pulses Z_{a1} , Z_{b1} , Z_{a2} , Z_{b2} etc., occur thus at equal intervals, whereby to fulfill an important condition for a distortion free demodulation accordingly, the envelope U corresponds to the modulation curve or signal at the transmitter. This applies particularly to transmission where the time-modulated pulses at the transmitter are also obtained from equidistant modulating values Z_{a1} , Z_{b1} etc., as shown and described in our U. S. Patent No. 2,435,496, 10 entitled Impulse modulation system.

As will be understood, the method according to the invention may be applied to other kinds of time-modulated pulses, for instance position-modulated pulses.

The arrangement for carrying out the method according to the invention will now be explained with reference to width-modulated pulses of the kind shown in Figure 2. The arrangement includes means for converting the time values a_1 , b_1 , a_2 , b_2 etc., of the width-modulated pulses into voltages which are proportional to these values, the voltage values Y_{b1} , Y_{b2} of the time values characterized by the position of the right-hand edges of the pulses being stored, in the manner described above. Furthermore, means are provided to enable the amplitude-modulated pulses Z_{a1} , Z_{b1} , Z_{a2} , Z_{b2} etc. to be produced at equidistant points P_{a1} , P_{b1} , P_{a2} , P_{b2} etc. which are proportional to the voltage values Y_{a1} , Y_{b1} , Y_{a2} , Y_{b2} etc. The conversion takes place in two separate operations, whereby the time value for the left-hand-edge, that is, at the beginning of the pulse, and the time value for the right-hand edge at the end of the pulse cause control systems to operate alternately.

The conversion of the time values of the left-hand pulse edges with reference to the equidistant points P_{a1} , P_{a2} , P_{a3} will be explained by reference to the diagrams of Figures 3a to 3d and the circuit arrangement shown in Figure 4.

The width-modulated pulses of amplitude U_0 , Figure 3a, received from the transmitter are applied to the control grid of a tube V_L together with a pulse voltage U_1 obtained from a suitable generator operated in synchronism with the received pulses. The local pulses U_1 have a phase lead of 90° relative to the received pulses U_0 . The two pulses applied to the control grid are shown in Figure 3a. The grid bias voltage of tube V_L is so selected that the working point is at the lower bend of the tube operating characteristic. An anode current will therefore only flow when both grid voltages are positive. Time-modulated pulses such as indicated by the shaded areas U_0+U_1 in Figure 3b will thus occur in the anode circuit of the tube. The width of these pulses corresponds to the time values a_1 , a_2 , a_3 , etc. of Figure 2. As soon as the voltage U_0+U_1 is positive and exceeds a certain value S , an anode current J_L flows through the tube V_L , charging the condenser C negatively at the terminal b through a resistance R . Owing to the voltage drop across the resistance R , the tube V_E will remain blocked until the current I_L ceases to flow. This is the case at the equidistance points P_{a1} , P_{a2} , P_{a3} etc. After this instant the tube V_E allows current to pass again, owing to its grid being positive. As a result, the condenser C is discharged by a discharging current J_E flowing through the tube V_E . The condenser should however only discharge until reaching zero voltage. In order to achieve this and to prevent charging in the opposite direction, a rectifier G^1 is connected in parallel with the condenser C .

As soon as the terminal b tends to become positive, a current flows through the rectifier, which prevents a voltage rise in the opposite direction. This charging and discharging process is illustrated in Figure 3c. Charging is completed at the points P_{a1} , P_{a2} etc. The charging voltage U_{ab1} , U_{ab2} etc. corresponds to the prevailing duration of the pulses shown in Figure 3b, and furthermore corresponds to the time values a_1 , a_2 , a_3 etc. of Figure 2. The actual amplitude-modulated pulses which occur at equidistant time positions are produced by means of a further tube V_a . To this end, part of the condenser voltage is applied through a potential-divider R_1 , R_2 , to the grid of tube V_a . Normally while a pulse is received, the tube is blocked. The grid of tube V_a furthermore has applied to it equally spaced short pulses U_2 , Figure 3d, through a resistance R_{ga} . The amplitude of these pulses is so selected as to just reach the starting point of the anode current. The proportional parts of the condenser voltages U_{ab1} , U_{ab2} etc. are thus added to the pulse voltages U_2 , so that the anode currents pulses of tube V_a are proportional to the condenser voltages and in turn to the time values a_1 , a_2 , a_3 etc.

The conversion of the time values of the right-hand pulse edges with reference to the equidistant points is illustrated in Figures 5 and 6. For the pulses shown in Figure 2, these time values are b_1 , b_2 , b_3 etc. These values have to be converted into proportional voltage values Y_{c1} , Y_{c2} etc. and stored during the periods S_1 , S_2 etc. in order to produce proportional impulses Z_{b1} , Z_{b2} etc. at the equidistant points P_{b1} , P_{b2} , as shown in Figure 2.

A circuit arrangement for converting the time values of the right-hand pulse edges is shown in Figure 6.

In the latter, the input grid of tube V_L' is excited by the width-modulated pulses U_0 received from the transmitter and a pulse voltage V_1 supplied by a local generator. The local pulses have a phase lag of 90° relative to the received pulses. The pulses on the control grid of tube V_L' are shown in Figure 5a. The grid bias voltage is again so selected that the working point lies on the lower bend of the characteristic operating curve of the tube. An anode current thus flows only when both the grid control voltages are positive. Thus time-modulated pulses occur in the anode circuit, such as are indicated by the shaded areas in Figure 5b. The width of these pulses corresponds to the time values b_1 , b_2 , b_3 etc. of Figure 2. As soon as the voltage U_0+U_1 becomes positive, an anode current J_L flows in the tube V_L' , which charges the condenser C' negatively at the terminal b' . The charging voltage V_{ab} attained after each pulse is proportional to the duration of the shaded pulses shown in Figure 5b. At the end of the pulses, voltages V_{ab1} , V_{ab2} etc. on the condenser C' remain stored for the periods S_1 , S_2 etc. up to the instants P_{b1} , P_{b2} etc. These instants lie in the middle between the equidistant points P_{a1} , P_{a2} , P_{a3} . At the instants P_{b1} , P_{b2} , P_{b3} etc. pulses with an amplitude proportional to the stored voltages V_{ab1} , V_{ab2} etc. are produced. This is achieved by rendering a parallel-connected tube V_E' current-conductive at the instants P_{b1} , P_{b2} etc. by applying the pulse voltage V_1 to the screen grid SG thereof. The screen grid is connected through a choke coil D with the anode A . The condenser discharges through the tube down to zero voltage. A rectifier G^1' is connected in

parallel with the condenser C' to prevent the latter from being charged with opposite polarity. A further tube V_a' P_{b2} , etc. is provided for producing the pulses at the instants P_{b1} (shaded areas in Figure 5c). The control grid of this tube is connected to a potential-divider which is arranged in parallel with the condenser C' . The control grid also has control pulses V_2 (Figure 5d) applied to it through a resistance; these pulses producing corresponding anode current pulses $J_{a'}$. The control pulses V_2 and the grid bias voltages are so selected that the control portion of the condenser voltage produces proportional current pulses.

The receiving arrangement combines the two arrangements shown in Figures 4 and 6. At the output end of this combined receiving arrangement there are obtained amplitude-modulated pulses according to Figures 3c and 5c. The pulses follow each other at constant intervals P_{a1} , P_{a2} , P_{a3} , etc. with twice as many pulses as there are width-modulated pulses at the input end of the arrangement. The pulse voltage U_0 supplied to both arrangements may for instance be derived from a common receiver in which the high-frequency pulse signals received through an aerial are amplified and converted into width-modulated pulses. Operating in synchronism with the received signal pulses is a generator producing the non-modulated control pulses U_1 and V_1 for both systems. The generator is provided with special means, whereby the pulses supplied to both amplifiers are phase-displaced by 90° compared with the non-modulated receiving pulses. Voltage U_1 leads the voltage U_0 and voltage V_1 lags behind the voltage U_0 .

The output ends of the amplifiers are connected in parallel so that there is double the number of pulses in the common output circuit. The pulses succeed each other at constant intervals of time, and have their amplitude modulated in accordance with the time values of the width-modulated pulses.

When time-modulated pulses of the kind shown in Figure 1 have to be converted into amplitude-modulated pulses, the arrangement shown in Figure 6 can be used. In this case it is also necessary to store the voltages Y_1 , Y_2 , Y_3 , etc. during the corresponding times S_1 , S_2 , S_3 , etc.

We claim:

1. In a system for receiving width modulated signal pulses of the type having equi-spaced starting edges and widths proportional to the instantaneous values of a modulating signal, a condenser with means for successively charging the same by the received signal current pulses, first switching means operated in synchronism with the pulse repetition frequency to initiate a discharge of said condenser after lapse of predetermined equal time intervals from each starting instant of successive signal pulses, and further switching means also operated in synchronism with the pulse repetition frequency and connected to said condenser for segregating amplitude modulated discharge current pulses of constant width spaced from each other by equal time intervals.

2. In a system for receiving width modulated signal pulses of constant amplitude and having equi-spaced starting edges and widths proportional to the instantaneous values of a modulating signal being received, an input circuit, a condenser, a constant current device connected between said input circuit to said condenser to successively charge said condenser by the signal current pulses to voltages proportional to the

respective pulse widths, first switching means operated in synchronism with the pulse repetition frequency and adapted to initiate a discharge of said condenser after lapse of predetermined equal time intervals from each starting instant of successive signal pulses, and second switching means connected to said condenser also operated in synchronism with the pulse repetition frequency for segregating amplitude modulated discharge current pulses of constant width spaced by equal time intervals from each other.

3. In a system for receiving width modulated signal pulses of constant amplitude having equi-spaced starting edges and widths proportional to the instantaneous values of a modulating signal being received, an input circuit, a condenser, a first electron discharge device connecting said input circuit to said condenser to successively charge said condenser by the signal current pulses to voltages proportional to the respective pulse widths, a second electron discharge device connected to said condenser with means for controlling the impedance thereof in synchronism with the pulse repetition frequency to initiate the discharge of said condenser after a lapse of predetermined equal time intervals from each starting instant of successive signal pulses, and a further electron discharge device controlled by impulses also in synchronism with the pulse repetition frequency, said last device being connected to said condenser to derive successive amplitude modulated discharge current pulses of constant width spaced by equal time intervals from each other.

4. In a method of receiving signal pulses having equi-spaced starting edges and widths modulated according to the instantaneous values of a modulating signal, the steps of converting said signal pulses into pulses of constant width and amplitude proportional with the respective widths of the original pulses, and variably delaying the converted pulses to produce substantially equi-spaced final pulses having amplitudes varying according to said modulating signal.

5. In a method of receiving modulated signal pulses of constant amplitude and having equi-spaced starting edges and widths proportional to the instantaneous values of a modulating signal, the steps of converting the received pulses into pulses of constant width and amplitude varying in proportion to the widths of the respective original pulses, and variably time delaying the converted pulses to produce substantially equi-spaced final pulses having amplitudes varying in accordance with said modulating signal.

6. In a method of receiving width modulated signal pulses of constant amplitude and having equi-spaced starting edges and widths proportional to the instantaneous amplitudes of a modulating signal, the steps of integrating the received signal current pulses to produce voltages having amplitudes proportional to the respective pulse widths, and variably storing said voltages and deriving equi-spaced signal pulses of constant width from the stored voltages having amplitudes varying according to said modulating signal.

7. In a system for receiving signal pulses having equi-spaced starting edges and widths modulated in accordance with the instantaneous amplitudes of a modulating signal, means for integrating the received pulses to produce voltages having amplitudes varying in proportion to the respective pulse widths, means for variably time delaying the integrated voltages and deriving

therefrom final voltage pulses of constant width at equidistant spacing intervals equal to the original pulse spacing intervals.

8. In a system for receiving width modulated signal pulses of constant amplitude and having equi-spaced starting edges and widths proportional to the instantaneous amplitudes of a modulating signal, means for integrating the received signal pulses to produce voltages having amplitudes proportional to the respective pulse widths, means for variably storing said voltages and for deriving therefrom final substantially equi-spaced voltage pulses of substantially constant width and having amplitudes varying in accordance with said modulating signal.

9. In a method of receiving width modulated signal pulses of constant amplitude having equi-spaced starting edges and widths proportional to the instantaneous amplitudes of a modulating signal, the steps of integrating the received signal pulses to produce voltages having amplitudes proportional to the respective pulse widths, and variably storing said voltages and deriving therefrom final equi-spaced voltage pulses of constant width and having a frequency equal to the original pulse repetition frequency and having amplitudes varying in accordance with said modulating signal.

10. In system for receiving width modulated signal pulses of constant amplitude having equi-spaced starting edges and widths proportional to the instantaneous amplitudes of a modulating signal, means for integrating the received pulses to produce voltages having amplitudes proportional to the respective pulse widths, means for variably storing said voltages and for deriving therefrom final substantially equidistant pulses of constant width, said final pulses having a frequency equal to the original pulse repetition frequency and amplitudes varying in accordance with the instantaneous amplitudes of said modulating signal.
